BURNER APPARATUS

Alonzo W. Ruff, York, Pa., assignor to York Oil
Burner Co., Inc., York, Pa., a corporation of
Delaware

Application September 18, 1940, Serial No. 357,324

7 Claims. (Cl. 158—77)

This invention relates to burner apparatus and particularly to an arrangement of air admission directors for controlling the shape and character of the combustion flame. The air control devices described hereinafter are especially suitable for use with horizontal rotary oil burners for directing and controlling the supply of primary air.

It is the object of this invention to provide an adjustable air control device for shaping the combustion flame of an oil burner to suit the combustion chamber space of any given installation.

The invention therefore enables a single type or model of burner to be used in a great many different kinds of installations and particularly without reference to the size and/or shape of the combustion space to which the burner is fitted.

It is a further object of this invention to provide an adjustable air control device of the character described that is located entirely within the fan casing of a rotary oil burner.

It is another object of this invention to provide an air control device within a horizontal rotary oil burner adapted to direct the flow of primary air axially, and in either a clockwise or counter-clockwise direction for producing a combustion flame of desired shape.

It is a further object of this invention to provide an air control device to produce a long cigar-shaped combustion flame, a short ball-shaped combustion flame, as well as flames, the shapes of which are variable at will as to length and lateral extent.

It is also an object of this invention to provide an air control device of the character described which may be adjusted to alter the shape of the flame, during operation of the oil burner, without disturbing combustion conditions, and without change in quantity of either air or oil supplied to the burner.

In explanation of at least one important and practical advance in the art accomplished by the instant invention, it obviates the necessity of dealers carrying in stock a very large number of burner parts of different sizes and shapes (e. g. spinner cups and air noses). This practice has been heretofore necessary, in order to enable proper installations to be made, especially with regard to the length and shape of the combustion flame to fit the varying sizes and shapes of combustion spaces. The selection of proper parts to suit a particular installation was largely a "cut and try" practice, so that not infrequently several trials and changes were necessary before a proper selection of parts had been made, i. e. a selection

which produced a suitable shaped flame for the particular installation. By contrast with this practice, in the use of the present invention, the burner may be completely set up or assembled at the factory and requires no changes or substitution of parts to render it suitable for any particular installation. The burner can now be completely installed and set in operation before adjusting the primary air supply for obtaining any desired flame shape.

Other objects and advantages of this invention will be apparent from the following description of the embodiment of the invention illustrated in the accompanying drawing in which:

15 Figure 1 is an elevation view, partly in section, of a horizontal rotary oil burner provided with my improved air control device.

Figure 2 is an elevation view of the inside of the front casing of the air fan shown in Figure 1 showing the directing blades provided to control air flow.

Figure 3 is an edge view of one of the air director blades and its supporting mount.

Figure 4 is a side view of the blade shown in Figure 3.

Referring to Fig. 1 of the drawing, the housing or enclosure for the electric motor of a horizontal rotary oil burner is indicated by the numeral 10. The motor drives the shaft 11 which carries an oil spinner cup 12 at the combustion chamber end for distributing and atomizing fuel oil supplied under pressure through the hollow shaft 11. The latter shaft also carries and drives a centrifugal fan 13 within a fan casing including a rear shell 14 secured to the casing 10, and a front shell 15 secured by bolts to the rear shell 14. Air is admitted to the hub of fan 13 through the motor casing and a control valve such as an adjustable, iris type diaphragm shutter, indicated by numeral 16. The fan shell and associated parts are appropriately supported with reference to a plate 17 suitably mounted at the fire opening of a furnace (not shown). The plate 17 carries a conical nozzle 18 directed through the furnace wall toward the furnace combustion chamber. The front fan shell 15 may be spaced from the plate 17 to provide an inlet for secondary air to the combustion zone that is delivered through the nozzle 18.

40 The front fan shell 15 supports a baffle plate 19 spaced from the shell 15 by a plurality of studs or bushings 20. The stationary baffle 19 lies closely adjacent the centrifugal fan 13 and may have its central or hub portion 21 curved out-

wardly toward the oil cup 12, to provide for smoother flow of air from the fan 13.

My improved air control device includes a plurality of flexible vanes or blades 22, preferably of spring steel or the like, positioned in the annular air passage between the baffle 19 and the inner wall of the front fan shell 15. The outer end of each blade 22 is detachably secured in one of the spacing bushings 20. See Figs. 2 and 3. The bushings 20 may be slotted so that the blade 22 having an offset curved portion or hump 23 is removably held therein, and is normally retained in assembled position by the baffle plate 19. The inner end of each blade 22 is preferably curved along one edge, as shown in Fig. 4, to conform to the surface of the flared central portion 21 of baffle plate 19. A flanged ring 24 is seated in a groove 25 on the inner face of and surrounding the central opening in fan shell 15. A flanged conical "air nose" 26 is carried by the ring 24, so that the ring and nose 26 may turn with respect to the front fan shell 15. As indicated in Fig. 2, the ring 24 may have a segment of its peripheral flange cut away providing an arcuate slot 27 cooperating with a pin 28 fixed in the fan shell 15 to limit the extent of angular or rotary movement of ring 24. A series of pins 29 project from the ring 24 and engage the sides of the flexible blades 22. Two such pins are associated with each of the blades 22, one on each side thereof, so that the blades will be deflected by one or the other of the pins, depending on the direction of rotation of the ring 24. An operating rod 30 secured to the flange of the "air nose" 26 and extending radially outward through the space between plate 17 and the front fan shell 15 is provided to permit external adjustment of the angular or rotational position of member 26 and ring 24. Movement of the rod 30, in one direction or the other, produces a correspondingly directed rotation of the ring 24, and by engagement of the pins 29 with the blades 22 the latter are uniformly and simultaneously flexed from a normal radial position. The blades 22 may be flexed to the positions shown in Fig. 2, or may be flexed to any desired intermediate degrees of curvature or to the position of opposite curvature, shown by dotted lines 22'.

The operation of the above-described air control apparatus is as follows: When the burner is placed in operation, the centrifugal fan 13 draws air through the casing 10 and builds up an air pressure in the outer annular chamber between the front fan shell 15 and the rear shell 14. Air under pressure flows from said annular chamber inwardly through the space between the inner wall face of the front fan shell 15 and the baffle plate 19, and is deflected outwardly over the outer surface of the oil cup 12 by the conical flared portion 21 of the baffle plate 19. This path of air flow is also confined by the conical "air nose" piece 26 which surrounds the oil cup 12. As the air passes between front fan shell 15 and baffle 19 it engages the blades 22 which in the deflected position of Fig. 2 will impart rotary movement to the air stream in a clockwise direction. By manipulation of the rod 30, the ring 24 may be rotated to cause the pins 29 to hold the blades in a radial position, or may be turned further to flex the blades to a position such as shown by dotted lines 22. A wide range of adjustment is possible to secure any desired degree of rotary movement of primary air entering the combustion zone from between the oil cup 12 and the member 26. The air may be

caused to rotate in the direction of rotation of oil cup 12, or in the opposite direction of rotation, or may be caused to pass into the combustion zone longitudinally without rotary movement. Minimum rotary movement of the primary air, corresponding to the normal radial position of the blades 22, tends to produce a long cigar-shaped combustion flame. Rotary movement of the primary air, induced by deflection of the blades 22 tends to produce a short ball-shaped flame. The total volume of primary air may be adjusted to suit combustion requirements by adjustment of the iris valve 16.

It will be readily apparent from the foregoing that the described air control device permits one to shape the combustion flame in any given burner installation to that best suited to the shape of the particular furnace firebox. The air flow may be controlled and varied while the burner is in operation and thus shutdowns for various trial adjustments are avoided.

Other advantages of my improved apparatus will be readily apparent from the above description of the embodiment illustrated. Obviously, variations in the nature and arrangement of the various elements will be evident to those skilled in this art, and this invention contemplates any equivalent structure within the scope of the following claims.

Having described my invention, what I claim and desire to secure by Letters Patent is:

1. In burner equipment for use with a combustion chamber—the combination with a fuel discharge nozzle adapted to deliver fuel into the combustion chamber; a fan; a shell encasing said fan and having a central annular air outlet; and an air nozzle in registry with said outlet and surrounding said fuel nozzle; whereby said fan is adapted to discharge air from said shell through said outlet and air nozzle and into the combustion chamber; of a plurality of flexible vanes arranged within the fan shell in the path of air flow from the fan to the shell outlet; and means engageable with said vanes for flexing the same for controlling the directional movement of the air delivered to the air nozzle between the limits of a spiral movement of selected pitch and a rectilinear movement to thereby control the shape of the burner flame with respect to the shape and dimensions of the combustion chamber.

2. In burner equipment for use with a combustion chamber—the combination with a fuel discharge nozzle adapted to deliver fuel into the combustion chamber; a centrifugal fan; a shell encasing said fan and having a central annular air outlet in the front wall thereof; a baffle plate positioned between said shell front wall and said fan to provide with said front wall an air passage from adjacent the periphery of said fan to an air outlet, said plate having a hub outwardly flared in the direction of said outlet; and an air nozzle in registry with said outlet and surrounding said fuel nozzle; whereby said fan is adapted to discharge air through said air passage, through said outlet and air nozzle and into the combustion chamber; of a plurality of flexible vanes radially arranged in said air passage, the inner end portion of each vane having a curved edge conforming with the curved surface of said baffle plate hub, and adjustable means engageable with said vanes for flexing the same for controlling the directional movement of the air delivered through said air nozzle and thereby control the shape of the burner flame

with respect to the shape and dimensions of the combustion chamber.

3. In burner equipment for use with a combustion chamber—the combination with a fuel discharge nozzle adapted to deliver fuel into the combustion chamber; a fan; a casing defining a chamber having an inlet for air from said fan and a central annular air outlet, said inlet being spaced from said outlet in a radial direction; and an air nozzle in registry with said outlet and surrounding said fuel nozzle; whereby air passing from said fan into said inlet flows through said chamber, through said outlet, through said air nozzle and into the combustion chamber; of a plurality of flexible vanes arranged within said chamber and in the path of air flow from said inlet to said outlet and extending between said outlet and said inlet and substantially radially from said outlet, and means for flexing each of said flexible vanes to positions in which the vanes provide curved surfaces to impart a desired direction to the path of the air issuing from said outlet into said air nozzle to thereby control the shape of the burner flame with respect to the shape and dimensions of the combustion chamber.

4. Equipment as recited in claim 3 wherein each vane is relatively thin and has a width substantially equal to the width of said chamber.

5. Burner equipment as recited in claim 3, wherein the vane flexing means comprises a ring-shaped element rotatably mounted on the casing, a plurality of pins projecting from said element for engagement with the vanes, there being at least one pin for engagement with each vane, and means operable from the exterior of said casing for adjusting said element through a limited range of angular movement, whereby said pins engage said flexible vanes to flex the same to positions in which the vanes provide curved surfaces to impart a desired direction to the path of the air issuing from said outlet and through the air nozzle.

6. Burner equipment as recited in claim 3, wherein each vane is secured adjacent one end thereof to the casing; and wherein the vane flexing means comprises a ring-shaped element 5 rotatably mounted in a recess in a wall of said casing, a plurality of pins projecting from said element for engagement with said vanes, there being a pair of pins for each of said vanes providing a pin on each side of each vane, and means operable from the exterior of said casing for adjusting said element through a limited range of angular movement, whereby said pins engage said flexible vanes to flex the same out of their radial positions to either side thereof, providing curved vane surfaces to impart a desired direction to the path of air issuing from said outlet into said air nozzle.

7. In burner equipment for use with a combustion chamber—the burner equipment having a fuel discharge nozzle adapted to deliver fuel into the combustion chamber; a centrifugal fan; a shell encasing said fan and having a central annular air outlet; and an air nozzle in registry with said outlet and surrounding said fuel nozzle; whereby said fan is adapted to discharge air from said shell through said outlet and air nozzle and into the combustion chamber; the improvement comprising: a plurality of radially disposed flexible vanes arranged within the fan shell in the path of air flow from the fan to said shell outlet, each vane having a fixed portion and a portion free to flex to either side of a radial line from the axis of said outlet through the fixed portion of the vane, and means engageable with said vanes for flexing the same for controlling the directional movement of the air delivered through said air nozzle to thereby control the shape of the burner flame with respect to the shape and dimensions of the combustion chamber.

ALONZO W. RUFF.
